Patented Oct. 17, 1916.

UNITED STATES PATENT OFFICE.

LUDWIG MELCHIOR, OF WILMINGTON, DELAWARE.

MAIL-BAG HOLDER.

1,202,011.

Specification of Letters Patent. Patented Oct. 17, 1916.

Application filed June 13, 1916. Serial No. 103,516.

To all whom it may concern:

Be it known that I, LUDWIG MELCHIOR, of Wilmington, in the county of New Castle and State of Delaware, have invented certain new and useful Improvements in Mail-Bag Holders; and I do hereby declare the following to be a full, clear, and exact description of the invention, such as will enable others skilled in the art to which it applies to make and use the same.

This invention relates to that class of mail delivery apparatus of the type shown and described in Letters Patent No. 909,007 granted to me January 5, 1909, the object 15 of the invention being to provide simple and efficient means for suspending the bag in position on the car for removal by a stationary crane adjacent the road bed.

In the accompanying drawings, Figure 1 20 is an elevation showing my improved bag holding mechanism in position to be engaged by the arm of a crane. Fig. 2 is an enlarged view of the bag holding arm. Fig. 3 is a similar view showing the position of the 25 parts immediately after the bag has been removed from the holder. Fig. 4 is a top plan view showing the supporting bar for the bag holder.

Referring to the drawings, 1 designates a 30 bar which is extended across the opening of a car door and journaled at its ends in bearings 2, the bar being held in its normal position by a coiled spring 3, one end of which is secured to a collar 4 of the bar and the 35 other to one of the bearings 2, such spring also acting as a buffer to take up shock. A handle 5 is secured to the bar for turning it, the bar being held in its adjusted positions by the engagement of a stud 6 with recesses 40 7 in one of the bearings 2. The bar 1 also forms the support for a catcher arm 8 of known form.

The bag holding mechanism comprises a bifurcated arm 12 which is disposed at an 45 angle to the bar 1 and has its shank fixedly secured thereto, the extensions of the arm being normally in a vertical plane, and a $\textcircled{O}$ shaped retaining member 13 which is pivotally mounted in the arm 12. The arms 50 of the retaining member normally lie in parallelism with the arms 12, and these arms of the retaining member have opposite longitudinal grooves which are designed to receive a loop 14 from which the mail bags

are suspended. I have shown this loop as 55 provided with notches 15 to accommodate a series of mail bag rings. The latter are placed on the loop through one side, a spring held catch 16 being employed for this purpose. The loop is held in its normal position within the retaining member by a spring arm 17 the hooked end of which engages the inner end of the loop. In order that the arms of the retaining member 13 60 may be normally held in parallelism with 65 the arms 12, I provide a spring catch 18 mounted in the shank of the bag holder, the outer end of the spring catch being designed to engage the inner end of the retaining member. Slight lateral pressure on the retaining member will release the connection 70 and permit the arm to swing freely on its pivot.

The operation of the device will be readily apparent. The bar 1 of the car is turned to 75 bring the bag holder into workable position within the car, and a mail bag which is to be delivered at a station on the road is suspended from a loop 14 and the latter placed in position in the retaining member 13, the 80 spring arm securely holding the loop in the retaining member as against accidental displacement. The retaining member is then properly aligned relatively to the holding arm 12 and so held by the spring catch 18. 85 The bar upon which the holder is mounted is then turned by the handle 5 and the holding arm with its complementary parts is projected beyond the car in position so that the receiving arm of a road crane will enter 90 the loop. The relative movement between the arm and the bag holder will effect a disengagement of the retaining member from its catch 18, when the arm engages the loop, permitting such member to turn on its pivot 95 so that the loop will be removed therefrom practically in a line with the direction of travel of the car, and without any strain upon the parts.

I claim as my invention:

1. A mail bag holder including a supporting member having a pair of spaced apart rigid arms, a retaining member pivoted to said arms, and a loop supported by said retaining member and to which a mail bag is 105 designed to be secured.

2. A mail bag holder including a supporting member having upper and lower out-

- wardly projecting rigid arms, a retaining member pivoted to said arms and having an open end and a loop supported by said retaining member and to which the mail bag 5 is designed to be secured.
3. An apparatus of the character described comprising a mail bag holder having upper and lower outwardly projecting arms, a retaining member pivoted to said 10 arms, a loop carried by said retaining member and to which a mail bag is designed to be secured, and means for normally holding said retaining member and loop in parallelism with said outwardly projecting arms.
- 15 4. An apparatus of the character described comprising a mail bag holder having upper and lower outwardly projecting arms, a retaining member pivoted to said arms and having outwardly extending portions, a loop fitted within the latter and to which a mail bag is designed to be secured, a spring catch carried by said holder for 20 normally maintaining said retainer in parallelism with the arms of said holder, and

resilient means for holding said loop in said 25 retainer.

5. In an apparatus of the character described, a bar pivotally mounted across a car door opening, means for holding said bar in operative and inoperative positions, 30 a mail bag holder carried by said bar and having upper and lower outwardly projecting arms, a retaining member pivoted to said arms and having an open end, a loop fitted 35 in the open end of said retaining member and to which a mail bag is designed to be secured, spring actuated means for holding said retainer in normal position, and resilient means for holding said loop as 40 against accidental displacement.

In testimony whereof, I have signed this specification in the presence of two subscribing witnesses.

LUDWIG MELCHIOR.

Witnesses:

JOSEPH HESS,
JOHN L. SCHMIDT.
